UNITED STATES PATENT OFFICE.

GEORGE E. MOLYNEUX, OF BAYONNE, NEW JERSEY.

STOPPING MECHANISM FOR SEWING MACHINES, ETC.

1,417,093.

Specification of Letters Patent. Patented May 23, 1922.

Application filed July 25, 1917. Serial No. 182,603.

To all whom it may concern:

Be it known that I, GEORGE E. MOLYNEUX, a citizen of the United States, and residing in the city of Bayonne, county of Hudson, 5 in the State of New Jersey, have invented certain new and useful Improvements in Stopping Mechanisms for Sewing Machines, Etc., of which the following is a specification, reference being had to the accompanying 10 drawings, forming a part hereof.

In the operation of high speed sewing-machines and analogous machines, it is necessary to bring the machine to rest quickly but without excessive shock and with 15 the parts in predetermined positions, as with the needle-bar of a sewing-machine in its highest position. Many stopping mechanisms have been designed to meet the requirements of such use, the action of most 20 of them being dependent upon the movement of a centrifugally controlled member so that the stopping mechanism shall not operate until the machine is slowed down to such an extent as to permit it to be stopped without 25 excessive shock. The present invention relates to stopping mechanisms of the general character referred to. The improved mechanism is not dependent, however, upon the movement of any centrifugally controlled member, but its operation is delayed 30 for a period of time following the disconnection of the driving mechanism which is proportionate to the speed of the machine, so that it does not become operative until the 35 machine is slowed down to a speed at which it can be stopped safely. The improved mechanism, moreover, is simple in construction and direct and certain in operation. The invention will be more fully explained hereinafter with reference to the accompanying 40 drawings in which it is illustrated and in which,—

Figure 1 is a view in elevation, with some parts in section, of so much of a sewing-machine with its driving and controlling mechanism as is necessary to enable the invention to be understood.

Figure 2 is a view of the improved stopping mechanism in longitudinal section on 50 the plane indicated by the broken line 2—2 of Figure 3, looking in the direction of the arrows.

Figure 3 is a view in section on the plane indicated by the broken line 3—3 of Figure 55 2, looking in the direction of the arrows.

Figure 4 is a detail view in section on the

plane indicated by the broken line 4—4 of Figure 3, looking in the direction of the arrows.

Figure 5 is a detail view in section on the 60 plane indicated by the broken line 5—5 of Figure 4, looking in the direction of the arrows.

Figure 6 is a view in section on the plane indicated by the broken line 6—6 of Figure 65 2, looking in the direction of the arrows.

In the application of the invention illustrated in the drawings, the bed-plate *a*, of an ordinary straightaway sewing-machine, is provided with the usual arm *b*, which supports the driving-shaft *c* with its pulley *d*. The latter is driven by a cord *d'* from a transmission device or driving means *d''* which is controlled, not only as to starting and stopping but as to its speed, by a controlling lever *d³*, which is connected by a link *d⁴* with a pedal *d⁵*. In machines of this character the pressure of the operator's foot upon the pedal *d⁵* is required to start the machine and the speed is proportionate to 75 the extent to which the pedal is depressed. When the operator's foot is removed from the pedal the transmission device is disconnected and the sewing-machine continues to run by its own momentum until it is stopped 80 by the operation of the stopping mechanism, as will be described.

For the purpose of cushioning the stopping of the machine a shock absorber of ordinary construction is provided. As 90 shown in the drawings the pulley *d* is fixed upon the driving shaft *c*, and mounted on the shaft, adjacent to the pulley and held thereto by screws *e'*, is a disk *e*. A stop-lug *e²*, for cooperation with the relatively 95 fixed stop-lug hereinafter referred to, is secured to the disk *e* and pulley *d* in such manner as to have a limited, rotary movement, having a neck *e³* which travels in a concentric slot *e⁴*, formed in the disk *e*, and 100 a head *e⁵* which stands between two springs *e⁶* and *e⁷*, located in a recess *e⁸* formed partly in the pulley and partly in the disk. The two springs *e⁶* and *e⁷* cushion the stop-lug *e²* and therefore the pulley *d*, the shaft *c*, and 105 their connected parts, respectively against the shock of stopping and the shock of the rebound.

Secured to the arm *b* is a block *f* and in the arm *b* and block *f* is mounted, so as to 110 have a limited longitudinal movement, a stop-rod *g* which carries at one end the rela-

atively fixed stop-lug g' . When the machine is running the stop-rod g is drawn to the left, as shown in Figures 1, 2 and 4, and the stop-lug is then clear of the path of the moving stop-lug e^2 , but when the machine is to be stopped the stop-rod is moved to the right so as to place the stop-lug g' in the path of movement of the stop-lug e^2 , the movement of the stop-rod being effected by a spring g^2 located in a chamber f' formed therefor in the block f . The stop-rod has fixed thereto, at its other end, a block g^3 , which is connected by a bell-crank lever g^4 and a link g^5 , with an interposed spring or yielding connection g^6 , to the pedal d^5 , so that when the pedal is depressed to connect the transmission and start the machine the stop-rod will be drawn to the left so as to take the relatively fixed stop-lug g' out of the path of the moving stop-lug e^2 .

Should the stopping mechanism become operative immediately upon the disconnection of the transmission, when the operator's foot is removed from the pedal, breakage of some of the parts would be likely to occur. It is necessary, therefore, that the action of the stopping mechanism shall be delayed somewhat, in order that the momentum of the machine shall be partly overcome by friction and the speed be reduced before the operative engagement of the stop-lugs takes place. For this purpose a detent is moved, when the machine is started, into the path of the movement of some part connected with the stop-rod g so as to prevent the immediate movement of the stop-rod into stopping position when the operator's foot is removed from the pedal, and provision is made whereby such detent is slowly withdrawn from its operative position. As shown the block g^3 is provided with a pin g^7 and a plunger h is mounted in an air cylinder h' which is provided with a restricted orifice h^2 and is secured to the block f . The plunger is pressed down normally by a spring h^3 , which may be fixed in the block f and bear on the extended upper end of the plunger, which is formed to engage the pin g^7 and hold the stop-rod retracted, its descent being retarded by the air in the cylinder, which escapes but slowly. The extended upper end of the plunger h is raised into the path of the pin g^7 , so as to prevent the operative movement of the stop-rod g by the movement of a lever h^4 , which is connected by a link h^5 with an interposed spring or yielding connection h^6 , with the pedal d^5 . Thereby, when the pedal is depressed to start the machine and to withdraw the stop-lug g' from the path of the stop-lug e^2 , the plunger h is raised so that it shall stand in the path of movement of the pin g^7 and prevent the operative movement of the stop-rod. The yielding connec-

tions in the links g^5 and h^5 permit the relative movement of the stop-rod and the plunger without the blocking of one by the other.

It has already been stated that the speed of the machine is proportionate to the extent to which the pedal is depressed, and as the plunger h of the dashpot is raised to an extent proportionate to the depression of the pedal and therefore to the speed of the machine, the time required for the complete descent of the plunger, and therefore for the release of the stop-rod, will also be proportionate to the speed of the machine, and the greater the speed of the machine the longer will be the time afforded for the slowing down, so that the engagement or connection of the relatively stationary member and the rotatable member will not be effected until the speed has been reduced to such an extent as to permit the stopping to be effected without danger of breakage. The size of the vent h^2 of the dashpot may be varied to suit the requirements of different machines.

The mode of operation of the improved stopping mechanism has been sufficiently described and will not require further explanation. It will be obvious that various changes in details of construction and arrangement may be made to suit different conditions of use and that the invention is not limited to the precise construction shown and arrangement herein.

I claim as my invention:

1. In a stopping mechanism, the combination of a relatively stationary member, a rotatable member, means to effect positive connection of said members, and a dashpot in operative relation with the connecting means to retard the operation thereof. 105

2. In a stopping mechanism, the combination of a relatively stationary member, a rotatable member, a stop-rod movable to effect operative connection of said members, a detent for said stop-rod, means to move the detent out of operative relation with the stop rod, and a dashpot in operative relation with said detent to retard the movement thereof. 110

3. In a stopping mechanism, the combination of a rotatable member carrying a stop-lug, a relatively stationary member, a stop-rod movable longitudinally in the relatively stationary member, and having a stop-lug, a detent to prevent movement of the stop-rod, means to move the detent out of operative relation with the stop rod, and a dashpot in operative relation with the detent to retard the movement thereof to release the stop-rod. 115

4. In a stopping mechanism, the combination of a relatively stationary member, a rotatable member, a stop-rod movable to effect operative connection of said members or disconnect same, means to move said stop- 120

- rod to disconnect said members, means to move said stop-rod to effect operative connection of said members, a detent to prevent movement of the stop-rod to effect operative connection of said members, means to move the detent into operative position, 5 means to move the detent from operative position, and a retarding device to retard the movement of the detent.
- 10 5. In a stopping mechanism, the combination of a relatively stationary member, a rotatable member, a stop-rod to effect operative connection of said members, a detent to prevent movement of the stop-rod, a single 15 controlling means for effecting operative movement of the stop-rod and the detent, and independent, yielding, operative connections between the controlling means and the stop-rod and detent.
- 20 6. In a stopping mechanism, the combination of a relatively stationary member, a rotatable member, a longitudinally movable stop-rod, a spring to move the same into
- operative position, a spring-pressed detent moved by its spring into inoperative position and movable in opposition to its spring, 25 to prevent movement of the stop-rod under the influence of its spring, a single controlling pedal, and independent connections between said pedal and the stop-rod and detent to move the same in opposition to their 30 actuating springs.
7. In a stopping mechanism, the combination of a relatively stationary member, a rotatable member, a longitudinally movable, 35 spring-pressed stop-rod, a spring-pressed detent to prevent movement of the stop-rod under the influence of its spring, a single controlling pedal, and independent connections between said pedal and the stop-rod 40 and detent to move the same in opposition to their actuating springs, said connections including each a yielding member.

This specification signed this 23d day of July, A. D. 1917.

GEORGE E. MOLYNEUX.
